UNITED STATES PATENT OFFICE.

CLYDE CONNER, OF MARIETTA, OHIO.

ATTACHMENT FOR BUFFING-LATHES.

1,076,022.

Specification of Letters Patent.

Patented Oct. 21, 1913.

Application filed October 17, 1910. Serial No. 587,581.

To all whom it may concern:

Be it known that I, CLYDE CONNER, a citizen of the United States, residing at Marietta, in the county of Washington, 5 State of Ohio, have invented certain new and useful Improvements in Attachments for Buffing-Lathes, of which the following is a description, reference being had to the accompanying drawings, forming a part 10 hereof.

My invention relates to an improvement in an attachment for buffing lathes and has for its object to provide an attachment whereby the buffs will give greater service 15 and capable of being easily and readily attached and detached.

Another object is to provide a device in which the polishing wheels, for example an emery, a cloth and a brush wheel will all be 20 in proximity so that no time will be wasted in moving from one wheel to another; also to provide a device that will be easy to construct and cheap to manufacture.

With these and other ends in view my in- 25 vention consists in certain novel features of construction and combination of parts as will be hereinafter fully described and pointed out in the claim.

In the accompanying drawing which repre- 30 sents a sectional view of my improved device, 1 is a suitable frame or support provided with bearings 2 in which rotates the shaft 3. A belt wheel 4 is located on the shaft 3 at 5. The shaft 3 is exteriorly 35 threaded at 6 and provided with a threaded longitudinal recess 7.

8 is a screw-threaded mandrel tapered at 9 provided with a flange 10 near one end thereof.

40 11 is a small hole running transversely through the flange 10 the object being that a small bar may be inserted therein when it is desired to attach the mandrel to or detach it from the shaft 3.

45 12 are two small washers preferably two inches in diameter which clamp a buff wheel 13 against the flange 9, and 14 is a nut which securely locks the same.

It will be seen that although the diameter

of the opening in the center of the buff 50 wheel may be greater than the diameter of the mandrel the buff wheel will be securely held in place by its two washers 12 and nut 14.

15 is a brush wheel located on the tapered 55 portion of the mandrel 9 and 16 is a cutting wheel carried by the shaft 3. I have only shown one buff wheel carried by the mandrel 9 but more than one may be used if desired.

It will be readily seen that with my im- 60 proved device that buff wheels may be used until they have been practically worn away instead of discarding them when they have worn down to the level of the five or six inch flanges that are ordinarily used to 65 clamp the buff wheels in position. The three polishing wheels also being in close proximity do away with any waste of time that would be occasioned if the wheels were on different machines.

Having thus described my invention, what I claim is:

A buffing lathe comprising a fork shaped frame with suitable bearings, a shaft sup- 75 ported in said bearings, a pulley mounted rigidly on said shaft between said bearings, said shaft having at one end an exteriorly threaded portion, a threaded recess extending longitudinally thereof, a mandrel, exter- 80 riорly threaded at one end to engage the above mentioned recess, the other end of said mandrel having a tapering threaded extremity, a threaded cylindrical portion merging therewith, a collar extending around said mandrel and formed integral 85 therewith, said collar separating the two threaded end portions of said mandrel, a polishing wheel upon said shaft, a polishing wheel upon the threaded cylindrical portion of said mandrel and a second polishing 90 wheel upon the tapered extremity of said mandrel.

This specification signed and witnessed this 3rd day of October A. D. 1910.

CLYDE CONNER.
